Primary Examiner — Robin V Webster*Assistant Examiner* — J. Thorn, Sr.(74) *Attorney, Agent, or Firm* — DLA Piper LLP (US)(57) **CLAIM**

The ornamental design for male underwear, as shown and described.

DESCRIPTION

FIG. 1 is a front perspective of male underwear in accordance with the present invention;

FIG. 2 is a front view thereof;

FIG. 3 is a right view thereof;

FIG. 4 is a left side view thereof;

FIG. 5 is a back side view thereof;

FIG. 6 is a top view thereof;

FIG. 7 is a bottom view thereof; and,

FIG. 8 is an exploded view thereof, illustrating openings between the front pouch and the main body of the underwear.

The broken lines in the drawings depict environmental subject matter and form no part of the claimed design.
